UNITED STATES PATENT OFFICE

171,427

FUEL TANK AND HOLDER THEREFOR

Mahlon C. Snyder, Hamburg, N. Y.

Application February 10, 1953, Serial No. 23,542

Term of patent 14 years

(CL. D14—3)

To all whom it may concern:

Be it known that I, Mahlon C. Snyder, a citizen of the United States of America and residing at Hamburg, in the county of Erie and State of New York, have invented a new, original, and ornamental Design for a Fuel Tank and Holder Therefor, of which the following is a specification, reference being had to the accompanying drawings forming part thereof.

Fig. 1 is a top plan view of a fuel tank and holder therefor embodying the present invention.

Fig. 2 is a side elevational view thereof.

Fig. 3 is an end elevational view, viewed from the right of Fig. 2.

Fig. 4 is a bottom plan view thereof.

Fig. 5 is a side elevational view, viewed from the opposite side as viewed in Fig. 2.

Fig. 6 is an end elevational view, viewed from the opposite end shown in Fig. 3.

Fig. 7 is a perspective view thereof.

I claim:

The ornamental design for a fuel tank and holder therefor, substantially as shown.

MAHLON C. SNYDER.
